UNITED STATES PATENT OFFICE.

ALBERT E. MAYNARD, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

SPECTACLE-FRAME-COATING MACHINE.

Application filed June 11, 1920. Serial No. 388,127.

To all whom it may concern:

Be it known that I, ALBERT E. MAYNARD, a citizen of the United States, residing at Southbridge, in the county of Worcester and 5 State of Massachusetts, have invented certain new and useful Improvements in Spectacle-Frame-Coating Machines, of which the following is a specification.

This invention relates to improvements in 10 spectacle making machines and has particular reference to a novel and improved construction of machine for use in the formation of temples, eye wires or other parts for spectacle mountings, in which the same are to 15 be provided with a non-metallic coating or lacquer.

One of the leading objects of the present invention is the provision of a satisfactory construction of machine for use in the formation 20 of a coating or lacquer on a large number of parts for a completed spectacle or eyeglass frame in a simple and efficient manner.

A further object of the present invention 25 is the provision of a machine which shall automatically withdraw the articles in such manner from the coating bath that the surface tension and adhesive properties of the bath will cause a uniform coating to be deposited on the several articles.

A further object of the present invention 30 is the provision of a novel and improved holder for use in connection with my machine which will serve to engage a plurality of articles and retain them in proper relationship during the several steps in the process 35 of coating the articles, thus facilitating the process of manufacture.

Other objects and advantages of my improved construction should be readily apparent by reference to the following specification taken in connection with the accompanying drawings, and it will be understood that I may make any modifications in the 40 specific details of construction shown and described within the scope of the appended claims without departing from or exceeding the spirit of the invention.

Figure I represents a front view of a machine embodying my improvements.

Figure II represents a side elevation thereof.

Figure III represents a vertical sectional view through one of the racks.

In the drawings, the numeral 1 designates 55 the base or frame of the machine having rising therefrom the guides 2 which are preferably of diamond or similar shape in cross section and have rotating thereon the guide wheels 3 of the carriage 4. It will be noted 60 that I have shown these guide wheels as consisting of two at one side of the machine and an intermediate one at the opposite side, while the carriage is in the form of a spring 65 frame member resiliently pressing the guide wheels towards the supports so that the carriage is held in an extremely steady position with sufficient frictional engagement to prevent undue movement in either direction so that a very satisfactory slow steady rise of 70 the carriage may be obtained. To effect this lifting movement I preferably make use of the shaft 5 suitably journaled in the frame above the carriage provided with the small winding drum 6 with side flange portions 7. 75 This drum is loosely mounted upon the shaft 5 and held to rotate therewith when desired through a suitable clutch mechanism, such as the washers 8 and 9 on the shaft, the washer 8 being suitably rigidly secured on or formed integral with the shaft 5 and the washer 9 being held against the adjacent flange 7 of the drum 6 by a spring 10 whose tension may be regulated through adjustment 80 of the nut 11. The purpose of this construction is to allow of longitudinal depression of the frame or carriage 4 when desired at a rapid rate, while the clutch will hold the drum to turn at a very slow rate to wind up the carriage as the shaft 5 is rotated; any 85 suitable mechanism, such as the large worm gear 12, worm 13 and drive pulley 14, may be applied to aid in reducing the speed from the driving member, such as the motor 15' to the shaft 5 and insure the movement being 90 at a slow but steady or non-jerking rate.

Secured to the lower part of the carriage 4 are the transverse arms 16 provided with the recesses or notches 17 to receive the arms 18 of the work holders, these arms 18 being 100 preferably in the form of transversely extending bars which for purposes of illustration have been shown as affording supports for spectacle temples, having the pins 19 extending through the usual screw apertures 105 in the temple butts so that the temples are hung thereon. Depending from the bar 18 are the arms 20 to which are secured the

round rod 21 slotted about half way through, as at 22, to provide an individual slot for each temple, thus guiding the temple so that it will hang straight, and having 5 sufficiently close engagement therewith so that swinging or dropping off tendency of the temple is reduced to a minimum.

In operation a bath of suitable lacquer or coating material is placed in the receptacle 23 and the carriage 4 lowered till the articles to be coated are immersed to the desired depth, after which the shaft 5 and thus the drum 6 are rotated to slightly wind up the flexible cord or connection member 10 15 24, gradually withdrawing the articles to be coated from the bath. This operation may be repeated any desired number of times until a coating of the desired thickness, color or flexibility has been provided. 20 In certain instances a single coat will be found sufficient, while in other cases more than a single coat is desired. Also in the case of temples or other articles it may be desirable to have a slight enlargement at the 25 terminus, such as the pear tip and ball tip, or other configuration to relieve the ear.

After the temple is thus coated it is allowed to dry and harden, which may be facilitated by revolving in a centrifugal machine. The construction of this machine 30 may be embodied in a separate application.

I would call particular attention to the advantage attained by providing a temple or frame coated in this manner, in that it 35 secures the strength and rigidity advantages of the ordinary frame coupled with the fact that with such a coating, which is impervious to the action of perspiration, the frame is prevented from tarnishing or discoloring due to the action of the salts of the body upon the material of the frame, thus providing a much more sanitary and safer article of wear than the old plain metallic frame, and yet a coating secured which is 40 45 sufficiently thin as to not unduly add to the size or weight of the parts and of maximum desirable appearance.

If desired, in place of a special article clamping device upon the centrifugal machine, however, to steady the articles dur-

ing the entire handling operation, and to facilitate preparation of the racks away from the carriage, I may secure to one of the vertical arms 20, or any other suitable portion of the rack, a hinged cross member 55 32 which may be swung against the articles and the bar 21 as soon as the articles being coated have been mounted in position, being locked by a suitable fastening device as at 33, the articles being securely retained at all 60 times in the rack irrespective of handling of the rack, and being capable of ready inter-change from one machine to another, and being impossible of separation from the rack until the locking device 33 has been 65 released.

I claim:

1. A device of the character described including a carriage having supporting arms and a plurality of interchangeable rack 70 members having portions for interlocking engagement with the arms said rack members each having article receiving projections and additional article steadyng recesses aligned with the projections to steady 75 articles mounted thereon.

2. In a device of the character described, a work holding rack comprising a main frame portion, a cross piece carried by the frame portion having a plurality of work receiving projections, a second cross piece disposed beneath the first and having a plurality of recesses formed therein corresponding in number and position to the work receiving projections of the first cross piece 85 whereby said recesses will receive the work suspended from the projections and hold the same against transverse displacement, and a clamp member carried by the frame having portions overlying respectively the projections and the recesses to prevent disengagement of the work from either of said parts.

In testimony whereof I have affixed my signature, in presence of two witnesses.

ALBERT E. MAYNARD.

Witnesses:

ALICE G. HASKELL,
ESTHER M. LAFLER.
